ABSTRACT OF THE DISCLOSURE

Apparatus for continuously casting metal strip on a continuously cooled moving belt includes means around which the belt is trained to form a small dependent loop within a larger loop, and end pieces that cooperate with the small loop to make a reservoir into which molten metal is teemed and in which it solidifies against the inside surface of the belt.

Molten metal has heretofore been continuously cast into strip by bringing it into contact with a chill roll or pair of rolls, a ring, a substantially flat endless belt, or between a ring and a belt. Apparatus which solidifies the metal against the convex surface of a roll or ring the external surface of which is immersed in the molten metal has the disadvantage that the metal solidifies from the surface of the pool, on which float undesired metalloids, fragments of refractory slag, oxides, gas bubbles and other impurities. Apparatus which casts the molten metal on a flat belt wherein the belt contains a pool of metal must have edge barriers of some sort which are difficult to maintain in operating condition. Apparatus has been proposed to cast molten metal on the inside surface of a ring with integral end pieces, but the problem then becomes that of getting the cast strip out of the ring. Suggestions have been made to spiral the cast strip out through an open end of the ring but unless a very large diameter ring is employed this creates difficulties except for narrow strip of ductile material.

There is, however, a very real advantage in casting strip against the inside of a ring or like concave surface which contains the molten metal pool. The bottom cast material is free from the floating contaminants above mentioned.

It is an object of my invention therefore to provide apparatus for continuously casting strip from the bottom of a pool of molten metal, and withdrawing it therefrom. It is another object to provide such apparatus which casts the metal against the concave surface of a moving belt. It is another object to provide such apparatus which permits removal therefrom of wide metal strip of a variety of properties without difficulty. Other objects of my invention will appear in the description thereof which follows:

I have found that the objects above mentioned are achieved with apparatus in which an endless metal belt is trained into an open top loop on the inner surface of which the strip is cast. Embodiments of my invention presently preferred by me are illustrated in the attached figures to which reference is now made.

FIG. 1 is an isometric view of apparatus of my invention, some details of which are omitted for the sake of clarity.

FIG. 2 is an isometric view of a modified form of the apparatus of my invention.

FIG. 3 is an isometric view of a portion of a further modified form of the apparatus of my invention.

FIG. 4 is a diagrammatic sketch of auxiliary strip bending apparatus used with my invention.

In my apparatus, an endless metal belt is trained around a plurality of rolls having the axes parallel. Two of those rolls are positioned uppermost and are spaced

2

from one another. The belt is looped over those rolls and depends therebetween to form an inner loop. The inner loop is maintained in a circular position by two circular end pieces. Molten metal is introduced into the reservoir formed by the inner loop and its end pieces to form a pool in the bottom thereof. As the belt travels around the rolls molten metal from the pool solidifies against the inner surface of the inner loop as a relatively thin strip which emerges from the reservoir through its open top portion between the two rolls above mentioned. This cast strip is then sheared or rolled or otherwise disposed of.

FIG. 1 illustrates a working form of the apparatus of my invention. An endless metal belt 10 passes around upper rolls 11 and 12 and lower roll 14. For a purpose to be described, an adjustable tracking roll 30 is spaced a distance from roll 11 and an adjustable tension roll 31 is positioned so as to cause the belt 10 to travel around approximately half the circumference of roll 30. A second idler roll 32 is positioned below roll 31 so that the belt 10 from roll 31 passes around roll 32 and back to roll 14. Inner loop 15 of belt 10 passes around a pair of cylindrical end pieces 33 and 34 so as to form a reservoir for molten metal. End piece 33 is carried by shaft 35 which is journaled in housing 36 and end piece 34 is carried by shaft 37 which is journaled in housing 38. Shaft 40 of roll 14 is driven by a motor 41 through gear reducer 42.

Above roll 14 in housings 48-48 are positioned pinch rolls 49 and 50 with their axes parallel to roll 14. A launder or feedpipe 52 is positioned so as to discharge metal in the gap between rolls 11 and 12 into the reservoir formed by inner loop 15.

Roll 30 previously mentioned is mounted in a housing 53 which is adjustably supported on a base 54. The position of roll 30 is adjusted by conventional means so as to cause belt 10 to track properly around the rolls and the circular end pieces of my apparatus. Roll 31 is mounted so as to be adjusted by conventional means not shown to maintain the desired tension in belt 10.

Each end piece 33 and 34 comprises a metal shell 56 provided with a refractory lining 57. The outer face of each shell 56 extends radially as a flange 78, between which flanges belt 10 is confined laterally. The outside surface of inner loop 15 is supported by a plurality of rolls such as roll 58, arranged circumferentially so as to sustain the weight of the molten metal in the loop. Cooling liquid spray nozzles 59-59 are positioned around the outer surface of inner loop 15 so as to cool the belt 10 continuously as it travels around end pieces 33 and 34.

In the embodiment of my apparatus shown in FIG. 2, the rolls 61 and 62 which define the open portion of inner loop 15 are not located in a horizontal plane but in a tilted plane so that the opening they define is not the uppermost portion of inner loop 15. Rolls 63 and 64 which provide for the outer loop are likewise displaced from the arrangement shown in FIG. 1. One circular end piece 65, otherwise similar to end pieces 33 and 34 above described, is provided with a central opening 66 through which the launder or feedpipe 67 introduces molten metal into the reservoir formed by the end pieces and inner loop 15. Each end piece 65 is supported by one or more lower rolls 76 formed with a circumferential groove 77 into which flange 78 of end piece 65 fits. Rolls 61 and 62 are provided with like grooves 77, which also engage flange 78. Belt 10 travels around rolls 61, 62, 63, 64, and end pieces 65, and the solidified strip 22 is removed as the belt 10 passes around roll 62 in clockwise direction. If it travels counter-clockwise, the strip 22 is removed as belt 10 passes over roll 61. The external surface of loop 15 is cooled by cooling spray nozzles, not shown, similar to nozzles 59 in FIG. 1.

The inside upper portion of end piece 66 is heated by a gas burner 84.

In the embodiment of my invention illustrated in FIG. 3, the inner loop 15 of belt 10 is made shallow. The molten metal reservoir is formed by loop 15 and stationary segmental side boards or end pieces 68 and 73 disposed parallel to each other at the margins of belt 10 between rolls 11 and 12. End pieces 68 and 73 are made of refractory material or of the same metal as is being cast and are prevented from moving upward and from turning by static restraints 79 and from moving outwardly by rotating contour rings 69 and 70, respectively, which are made of high thermal conductivity material. These rings are supported by rolls 11 and 12 and bear against the margins of belt 10 throughout inner loop 15. Contour ring 70 is maintained in an upright position by flanged rolls 71 and 72 which bear against the upper portion of its circumference and contour ring 69 is provided with like rolls 74 and 75. The belt 10 is held against the arcuate edges of end pieces 68 and 73 and in contact with contour rings 69 and 70 by the rolls 11 and 12 and, if necessary, by auxiliary rolls such as roll 58 shown in FIG. 1. Contour rings 69 and 70 are not driven rings but are rotated by the friction of belt 10. In this embodiment of my invention, belt 10 is moved by driving rolls 11 and 12, or other rolls around which belt 10 is trained. Molten metal is conveniently introduced into inner loop 15 through the open end of contour ring 69 or 70 by a launder such as launder 67 in FIG. 2. The solidified strip 22 is taken off as belt 10 passes over roll 12. The outer surface of loop 15 is cooled by cooling fluid spray nozzles 59-59. The return path of belt 10 is not shown, as it is similar to that of FIG. 1.

The operation of my apparatus will be described with particular reference to FIG. 1. Counter shaft 40 is rotated so as to cause belt 10 to travel around the belt rolls there illustrated. The portion of belt 10 which passes around end pieces 33 and 34 forms a clockwise travelling inner loop 15, as has been described. The cooling liquid spray nozzles are adjusted to spray cooling liquid on the outer surface of inner loop 15. Molten metal is poured into the reservoir formed by inner loop 15 and end pieces 33 and 34 through launder 52. As the belt 10 rotates molten metal freezes against the concave surface of that portion of belt 10 which forms inner loop 15 and passes out of that reservoir where belt 10 travels around roll 11. The solidified strip 22 so formed is lead to pinch rolls 49 and 50 and is continuously removed thereby. I have found that if the margin of belt 10 overlaps the cylindrical surfaces of end pieces 33 and 34 there is no leakage of molten metal at the interface. The continuous cooling of the outer surface of inner loop 15 by cooling liquid spray nozzles 59 tends to freeze any metal which penetrates between those faces.

In some circumstances it may be convenient to take the solidified strip out of my apparatus in a path other than one tangential to the inner loop 15. FIG. 4 illustrates diagrammatically apparatus suitable for use in conjunction with the apparatus of FIG. 1 for bending the strip back over the roll adjacent its take off point. Positioned above roll 11 and tangent to the outside of the path of the strip 22 is fulcrum roll 81. Tangent to the inside of the path of the strip 22 and intermediate rolls 11 and 81 is positioned guide roll 82, and above it is positioned roll 83 which is adjusted to hold the solidified strip 22 against fulcrum roll 81. The strip 22 leaves the belt 10 as that belt passes over roll 11. The strip then passes over roll 82 and between rolls 81 and 83. As it leaves roll 81 it is bent into the desired take off path.

In apparatus for casting strip on a cooled belt such as I have described, the surfaces in contact with the molten metal against which the molten metal does not solidify necessarily tend to extract heat from it. Where those surfaces move with the belt, as do end pieces 33 and 34 of FIG. 1, elements of the surface pass from positions below the metal level to positions above the metal level as the

end pieces rotate. In the latter positions, those elements give off heat. It is therefore desirable from the standpoint of heat conservation to maintain a deep pool of molten metal in inner loop 15. Where those surfaces do not move with the belt, as is the case with elements 68 and 73 in FIG. 3, it is desirable from the heat loss standpoint not to extend them above the molten metal level any farther than is necessary, and apparatus of this type is well suited for casting metal from a relatively shallow pool. In apparatus of the type shown in FIG. 2, it is frequently desirable to supply heat to the portion of rotating end piece 66 above the level of the molten metal, as by gas burner 84, to make up heat losses from the end piece. Under some circumstances, I find it desirable to heat the upper portions of end pieces 33 and 34 of FIG. 1 in the same way. Any conventional method of heating those surfaces is satisfactory.

The endless belt 10 common to all the embodiments of my invention herein described is caused to move by driving one or more of the rolls around which it is looped. In FIG. 1, roll 14 is driven. In the apparatus shown in FIG. 2, one or more of rolls 61, 62 and 76 which support end piece 65 are driven or, if more convenient, the drive is furnished through one or both of rolls 63 and 64. In the embodiment of FIG. 3, it is desirable to drive one or both of rolls 11 and 12. The solidified strip 22 is in all embodiments withdrawn from my apparatus by suitable positioned driven pinch rolls, such as rolls 49 and 50 in FIG. 1. The strip after leaving those rolls is further rolled to reduce its thickness or is otherwise treated as is desired.

I claim:

1. Apparatus for the production of cast metal strip by the continuous solidification of molten metal on a chill surface comprising an endless metallic belt, means around which the belt is trained so as to form a dependent loop, said means including a pair of discrete end pieces which form with the loop an arcuate chamber adapted and adjusted to hold a segmental pool of molten metal, the chamber being open over a portion of its upper periphery, means for supplying molten metal to the chamber, means for applying cooling fluid to the belt around the outside of the loop so as to cause molten metal to solidify against the inside of the loop, means for withdrawing solidified strip from the belt through the open portion of the chamber, and means causing the belt to travel around the training means.

2. Apparatus of claim 1 in which the means around which the belt is trained include a pair of parallel spaced apart rolls which with the end pieces define the open portion of the chamber periphery.

3. Apparatus of claim 1 in which the means for supplying molten metal to the closed chamber are positioned to deliver the metal into the open portion of the chamber periphery.

4. Apparatus of claim 1 in which the end pieces comprise rotatable disks which contact the inside margins of the belt and travel with it, and including means for rotatably supporting those disks.

5. Apparatus of claim 4 in which the inside margins of the belt overlap circumferential edge portions of the rotatable disks.

6. Apparatus of claim 4 in which the circumferential edges of the rotatable disks are provided with radial outwardly extending flanges adjacent the outer faces of the disks and the inside margins of the belt overlap the circumferential edges of the rotatable disks and abut the flanges.

7. Apparatus of claim 1 including supporting means positioned around the outside of the loop.

8. Apparatus of claim 7 in which the supporting means comprise a plurality of freely rotatable rolls the axes of which are parallel.

9. Apparatus of claim 1 including means for maintaining tension in the belt.

10. Apparatus of claim 1 including means for shifting

the belt transversely of its direction of travel to maintain tracking.

11. Apparatus of claim 1 including means for applying heat to the exterior surface of an end piece.

12. Apparatus of claim 1 in which one end piece is provided with an opening and the means for supplying molten metal to the closed chamber extend into that opening.

13. Apparatus of claim 1 in which the end pieces comprise rotatable disks provided with radial outwardly extending flanges adjacent their outer faces and including supporting rolls therefor provided with grooves which mate with those flanges.

14. Apparatus of claim 1 in which the end pieces comprise stationary segments, and including means for maintaining the circumferential edges thereof in sliding contact with the inside margins of the belt.

15. Apparatus of claim 14 in which the arcs of the segments are less than 180°.

16. Apparatus of claim 14 including means contacting the inside margins of the belt and travelling with it for 20 preventing outward movement of the segments.

17. Apparatus of claim 16 in which the means contacting the inside margins of the belt comprise rotatable rings.

18. Apparatus of claim 17 including grooved rolls positioned to maintain the rotatable rings upright, the grooves of the rolls mating with the rotatable rings.
